UNITED STATES PATENT OFFICE.

ANDREW J. SELZ, OF NEW ROCHELLE, NEW YORK, ASSIGNOR TO PAPER BOTTLE AND CAN COMPANY, INC., OF WILMINGTON, DELAWARE, A CORPORATION OF DELAWARE.

PAPER BOTTLE.

1,342,770.

Specification of Letters Patent. Patented June 8, 1920.

Application filed October 2, 1917. Serial No. 194,328.

To all whom it may concern:

Be it known that I, ANDREW J. SELZ, a citizen of the United States, and resident of New Rochelle, in the county of Westchester and State of New York, have invented a new and useful Improvement in Paper Bottles, of which the following is a specification.

The object of my invention is to produce a paper bottle which will be strong and durable, which will be simple to manufacture and inexpensive, and which may be readily packed in a minimum space for shipment without danger of causing the collapse of the bottles.

A further object is to provide a bottle of the above character having a very strong and rigid bottom.

A still further object is to provide a bottle of the above character having a very strong and rigid top.

A practical embodiment of my invention is represented in the accompanying drawings in which,

Figure 1 represents the blank from which the bottle is formed.

Fig. 2 represents in perspective, the bottle formed from the blank.

Fig. 3 is a bottom plan view of the bottle,

and

Fig. 4 is a detail section at the bottom of the bottle.

The blank from which the bottle is formed is scored and cut as follows:

Diverging score lines 1, 2, 3, 4, form five diverging side members 6, 7, 8, 9, 10, the members 6 and 10 of which are intended to overlap in the completed bottle. Transverse score lines 11, 12, 13, 14, 15, are located at the bases of alternating separate full and half-size bottom members 16, 17, 18, 19, 20. Transverse score lines 21, 22, are located at the bases of top members 23, 24, which top members are provided with score

lines 25, 26, 27, 28, and cuts 29, 30, 31, 32 45 forming flaps 33, 34, 35, 36, arranged to overlap the top sides of the bottle when completed. These top members 23, 24, also have holes 37, 38, therethrough. Cuts 39, 40, 41, 42 serve to separate the full and half-size 50 bottom members.

In the completed bottle, a very substantial and strong bottom of four thicknesses is formed by the bottom members 16, 17, 18, 19, 20. A very strong top of two thicknesses is 55 provided for the bottle by the members 23, 24, and their flaps 33, 34, 35, 36.

It is to be understood that the overlapping side members and flaps may be firmly glued or otherwise cemented and where the bottle 60 is to be used for liquids, the entire bottle may be treated with a suitable material such as paraffin, to render the same moisture-proof.

Bottles produced from blanks as herein 65 described will be very strong and durable and a number of them may be packed in a very small space for shipment without danger of their collapse.

What I claim is:

1. A tapered paper bottle comprising diverging side members, alternating separate full and half-size bottom members and one or more top members, said top member or members having oppositely arranged 75 depending flaps overlapping the upper portions of their adjacent side members.

2. A tapered paper bottle comprising diverging side members, alternating separate full and half-size bottom members and one 80 or more top members, said top member or members having a hole or holes therethrough for gaining access to the interior of the bottle.

In testimony, that I claim the foregoing 85 as my invention, I have signed my name this 27th day of September 1917.

ANDREW J. SELZ.
